UNITED STATES PATENT OFFICE

2,004,461

MANUFACTURE OF CIGARETTES

Sidney Waterfield Bunker, London, England, assignor to Filter Tips Limited, London, England, a British company

Application October 31, 1934, Serial No. 750,905
In Great Britain July 14, 1933

4 Claims. (Cl. 131—39)

This invention relates to the manufacture of cigarettes having cork or like tips with or without filter tips or like stub portions.

It has before been proposed to provide means in association with a continuous rod cigarette machine whereby a tipping strip is fed transversely in relation to the cigarette rod by mechanism which is reciprocatable as a whole in the direction of movement of the cigarette rod, the tips after cutting off from the tipping strip and pasting being applied to the cigarette rod and wrapped around the same by the provision of a succession of forming devices.

The present invention has for its object to provide an improved method of and means for applying cork tips to a pre-formed cigarette rod or tube.

According to the present invention the improved method for the production of cigarettes provided with cork or like tips comprises feeding lengths of tipping material longitudinally into engagement with a continuous cigarette rod or cigarette paper tube and positioning the lengths of tipping material on the rod or tube so that the seam of the tipping material is in alignment with or in definite relation to the seam of the cigarette rod or cigarette paper tube, and thereafter wrapping the lengths of tipping material around the rod or tube.

The invention furthermore includes the method for the production of cigarettes provided with cork or like tips which comprises continuously forming a cigarette rod or cigarette paper tube having a crimped seam and thereafter applying lengths of cork or like tipping material thereto.

According to the invention, moreover, apparatus for carrying out the method hereinbefore specified comprises means adapted to feed previously pasted lengths of cork or like tipping material longitudinally into contact with a continuous cigarette rod or cigarette paper tube and means for wrapping the lengths of tipping material around the rod or tube. The lengths of tipping material may be applied to the cigarette rod or tube by means of a drum device adapted to pick up the lengths of tipping material from a pasting device and to release such lengths after the latter have been brought into contact with and positioned on the cigarette rod or tube. The drum device may be adapted to pick up the lengths of tipping material by vacuum action. The lengths of tipping material may be wrapped around the cigarette rod or tube by means of a series of rollers or the equivalent.

The invention is hereinafter described by way

of example with reference to the accompanying diagrammatic drawing, in which:—

Figure 1 is a part sectional side elevation illustrating one embodiment; and

Figures 2, 3 and 4 are vertical sections respectively on the lines II—II, III—III and IV—IV, Figure 1.

In carrying the invention into effect according to one embodiment and with reference to the accompanying diagrammatic drawing, strips 1 of cork or the like may be applied to the continuous cigarette rod 2 by means of a drum 8 having holes 8a, such drum 8 being rotatable on an inner drum or sleeve 9 having a slot 9a and connected to a suction pump so that by vacuum action the strips 1 of cork or like tipping material may be picked up from a pasting and cutting device 10 and may be released after they have been brought into contact with the cigarette rod 2. The strips 1 may be wrapped around the rod 2, for instance, by a roller 3 and pairs of rollers 4, 4a, 5, 5a acting in series as illustrated in Figures 2, 3 and 4, so that the seam of the cork or like tip 1 coincides with or is in definite relation to the seam of the cigarette rod 2, which latter is subsequently cut off into lengths in the usual manner. Preferably the cigarette rod 2 has a crimped seam produced by a crimping device 6 of any suitable kind and the rod 2 may be guided to the cork tip-applying means by means of a tubular or other guide 7. The cigarette rod may contain a continuous filling of tobacco or may contain a composite filling consisting of alternate lengths of tobacco and filter tip or stub material.

It will be appreciated that, inasmuch as the seam of the cigarette paper case, which may be a crimped seam, is formed before the application of the cork or like tip, such seam is thereby strengthened in that a double seam is obtained.

Since the method of the present invention may be applied with equal advantages to the tipping of continuous cigarette rods or cigarette paper tubes, the terms "cigarette rod" and "cigarette paper tube" have been used synonymously in the appended claims.

What I claim is:

1. A method of applying tips to a moving cigarette rod, comprising moving an endless surface in contact with and at the speed of travel of the cigarette rod, feeding lengths of tipping material to said surface at spaced intervals for transfer to said cigarette rod, and wrapping said lengths of material about said cigarette rod.

2. A method of applying tips to a moving cigarette rod, comprising moving an endless surface

- in contact with and at the speed of travel of the cigarette rod, feeding a strip of tipping material toward said surface in the direction of movement thereof, severing lengths of said material, applying the severed lengths at spaced intervals on said surface, and transferring the lengths from the moving surface to said cigarette rod.
3. A method of applying tips to cigarettes, comprising guiding a continuous cigarette rod into engagement with the circumferential surface of a revolving member, feeding lengths of tipping material to the circumferential surface of said member in a direction substantially tangentially thereof, applying said lengths at spaced intervals to said surface, transferring said lengths of material

from said surface to said cigarette rod, and wrapping the transferred lengths about said rod.

4. A method of applying tips to cigarettes, comprising guiding a continuous cigarette rod into engagement with the circumferential surface of a revolving member, feeding lengths of tipping material at spaced intervals to the circumferential surface of said member in a direction substantially tangentially thereof, maintaining said lengths of material on said surface during travel toward the cigarette rod, releasing said length of material from said surface when brought into contact with said cigarette rod, and wrapping said lengths of material about said cigarette rod.
